UNITED STATES PATENT OFFICE.

JOHN LACEY WEST, OF ABINGDON, BERKS, ENGLAND.

MOLD FOR MAKING ROOFING TILES.

Application filed August 22, 1927, Serial No. 214,771, and in Great Britain August 28, 1926.

This invention relates to roofing tiles and has for its object to provide an improved mold for forming valley tiles for use with the common forms of interlocking tiles and is particularly applicable to the forming of 5 concrete valley tiles.

With the forms of mold and pallets previously employed for forming interlocking concrete tiles it has not been possible to form 10 valley tiles provided with the ridges and grooves corresponding to the ordinary plane interlocking tiles.

According to the present invention I form 15 interlocking valley tiles by molding them upside down upon a ridged pallet and forming an interlocking groove on the underside of the tile by means of a striker.

The invention also comprises the improved 20 means for forming the valley tiles hereinafter described and claimed.

In the accompanying drawings which illustrate the invention,

Fig. 1 represents an interlocking concrete 25 valley tile to produce which is the object of the invention,

Fig. 2 represents the frame for the pallet or mold on which the tile is produced;

Fig. 3 represents the frame with the pallet 30 in position;

Fig. 4 represents the rear portion of the frame with the vertical members tilted over to give access to the underside of the pallet for removal of the latter with the molded tile upon it;

Fig. 5 represents the front portion of the frame with the hinged rib-forming mold in 35 position.

The valley tile which has on each side two ribs *a* is shown in Fig. 1 and it is to be 40 understood that the central vertical line in this figure represents the bottom of the valley; at one side a channeled projection *b* is provided while at the other side a ridge *c* with an underneath channel *d* is provided.

The ordinary rectangular intermeshing 45 tile with which the valley tiles match are provided at one edge with a rib *c* which fits over the channeled projection *b*, a similar channeled projection being provided on the other edge.

The mold frame comprises a quadrilateral base *e* provided at the front with a hinged block *m* for forming the front portion of the tile and with side members or rails *j*, *k* be-

tween which the pallet *p* is placed and which 55 projects above the latter to an extent corresponding to the thickness of concrete required and thus act as striking-off gauges.

At the back of the base *e* vertical members *f*, *g* are hinged; these members interlock 60 with each other by a groove *D* and are held in vertical position by a rear hinged strut *h*.

The pallet or mold *p* is of ridged form and is provided with recesses *B*, *C* corresponding 65 to the ribs to be formed on the valley tile. The peak of the pallet is supported upon an angular seat *A* carried on the member *e*, and the edges are supported on ledges, one, *E*, of which is shown in Figs. 2 to 4.

A hinged nib-forming mold *l* is provided 70 with a recess *n* corresponding to the nib to be formed on the underside of the front of the valley tile. It is to be understood that the pallet is of ridged form and that the valley tile is molded upside down so that 75 the nib has to project upwards from the tile as molded.

The mold *l* is hinged at the side of the frame and normally occupies the raised position shown on Figs. 2 and 3 of the drawings. 80

Fig. 3 shows the parts in position for the concrete to be molded.

Concrete is then placed on to the pallet 85 and is caused to fill the recesses therein by means of a trowel or other suitable means; by means of an ordinary striker working 90 along the edges *f*, *j* and *g*, *k* the thickness of the concrete is determined. It now remains to form the nib *i* and the interlock channel *d* on the back of the tile. 95

To form the nib, the hinged member *l* is 100 swung over to the position shown in Fig. 5 and concrete is tamped into the recess *n*; the member *l* is then hinged back. To form the interlock channel *d* a striking rod *w* of rectangular section of which the end portions only are shown on Figs. 1 and 2 is driven 105 into the concrete in the edge of the tile, this rod resting in a notch *r* in the member *f* and against a ledge *s* on the front hinged block *m*; the rod is then slid out of the groove so formed.

The tile is now molded and now has to be removed on its pallet from the frame to a place where it hardens or "cures". 110

For this purpose the front block *m* is tilted forward on its hinge *F*, and the rear strut *h* is folded back thus enabling the vertical

members *f*, *g* to be hinged back as shown in Fig. 4 and permitting the operator to put his hand under the pallet and lift it out.

Although the form of the invention illustrated is specially intended for use in forming concrete tiles it may also be employed with suitable minor modifications to the forming of interlocking tiles of clay or other plastic material.

10 I claim:-

1. A mold for forming interlocking valley tiles comprising a hinged frame and a ridged pallet.

2. A mold for forming interlocking valley

15 tiles comprising a quadrilateral base member, rear hinged vertical members, a front hinged block, and a hinged nib-forming member.

3. A mold for forming interlocking valley tiles comprising a base member, rear hinged vertical members, an angular seat for the 20 peak of a pallet carried by one of said vertical members, ledges for the sides of the pallet carried by the base member, a front hinged block, and hinged nib-forming member.

25 In testimony whereof I affix my signature.

JOHN LACEY WEST.
